UNITED STATES PATENT OFFICE.

MICHAEL BRANCH, OF RICHMOND, VIRGINIA.

TYPE-WRITING MACHINE.

1,225,698.

Specification of Letters Patent.

Patented May 8, 1917.

Application filed August 16, 1916. Serial No. 115,311.

To all whom it may concern:

Be it known that I, MICHAEL BRANCH, a citizen of the United States, residing at Richmond, in the county of Henrico and 5 State of Virginia, have invented certain new and useful Improvements in Type-Writing Machines, of which the following is a specification.

My invention relates to new and useful 10 improvements in typewriting machines.

My invention relates to improvements in means for guiding paper around the revoluble cylindrical platens of a typewriting machine, so that the paper may be written on 15 close to the top and bottom edges and preventing the paper from bulging.

Another object of my invention is to overcome this difficulty and provide devices which may be readily applied to existing 20 machines, especially those of the "Underwood" front strike type, which holds the entire top edge and the entire bottom edge of a sheet of paper against the platen.

A still further object of my invention is 25 to provide a device of this character which can be readily attached and detached and is simple in construction and having certain details of structure and operation herein-after more fully described.

30 In the accompanying drawings—

Figure 1 is a front elevation of an Underwood typewriting machine, showing my improvement applied thereto;

Fig. 2 is a transverse vertical sectional 35 view taken on the line 2—2 of Fig. 1;

Fig. 3 is an enlarged perspective view illustrating the relation of the paper clips to the several rods of the usual roller mechanism.

40 Referring now to the drawings, 1 represents the platen which is provided with an axle 2 mounted in the frame 3, which is known as the platen supporting frame, and the said frame is supported by the movable

45 carriage, all of which is well understood and needs no further description. The platen frame is provided with a paper shelf 4, in rear of the platen and carries the forwardly extending fingers 5 forming guides for the 50 paper, as fully shown in Fig. 2 of the drawings.

Mounted within the frame 3 are the front and rear pressure-rolls 6 and 7, which bear

against the platen 1 and hold the paper tightly against the same. Carried by the 55 frame 3 between the rollers 6 and 7 is a shaft 8 which carries the arms 9 in which is mounted the shaft 10, directly below the shaft 9. These shafts 9 and 10 are for the purpose of supporting the springs 11 and 60 other working parts, all of which is well understood by those skilled in the art and needs no further description.

My improved paper guide consists of the 65 plates 12 and 13, which are attached to the rods or shafts 9 and 10, one of the said plates serving the same function as two of the guides now used on the Underwood typewriter, such as shown in Patent No. 838,328, and my improved guide plates also more 70 firmly hold the paper tight on the platen.

The plate consists of a body portion 14, curved to correspond with the periphery of the platen 1 and provided with a central cut-away portion 15 around which the metal 75 is struck up forming an outwardly extending beading 16 which strengthens the guide and allows it to be made of thin material and at the same time gives the proper resiliency, so that the guide will closely hug 80 the periphery of the platen. The end walls of the body are straight, as indicated at 17 and 18 and are then beveled inwardly, as indicated at 19 and 20, to a point slightly below the bottom of the central cut-away 85 portion 15. Extending from the beveled walls 19 and 20 are the beveled walls 21 and 22 which extend in the same direction; and, as shown in Fig. 2, are curved to correspond with the periphery of the platen.

90 At the lower end of the beveled walls 21 and 22 the plate is formed with a looped portion 23 which is adapted to be sprung upon the shaft 9 of the frame 3 and the body portion 14 extends upwardly under the pressure roller 6 and bears against the platen roller and firmly clamps the paper thereon. Below the looped portion 23 the plate is bent outwardly at 25 and extends on the outside of the shaft or rod 10. The pressure of 95 the curved portion on the rod 10 causes the looped portion to oscillate on the rod 9 and normally hold the body portion 14 firmly against the platen and such pressure is normally maintained so as to more firmly hold 100 the paper on the platen.

By this structure, it will be seen that the guide plates are readily attached by forcing the looped portion 23 over the rod 9 and can also be readily removed and are adapted to be applied to the ordinary Underwood typewriter of the front strike type.

Having thus described my invention, what I claim as new and desire to secure by Letters Patent, is:

- 10 1. In a typewriting machine having a platen, the combination with three rods adjacent the platen, a guide plate having a looped central portion to receive the center rod and having the upper end curved to pass under the upper rod and bear against

the platen, and the other end engaging the outer face of the lower bar.

2. In a typewriting machine having a platen, the combination with three rods adjacent the platen, of a metal guide plate supported by the center rod, and having one end passing under the upper bar and the opposite end on the outside of the lower bar. 20

In testimony whereof I affix my signature in the presence of two witnesses.

MICHAEL BRANCH.

Witnesses:

S. H. EVANS,
J. G. REITZEL.
